UNITED STATES PATENT OFFICE.

HERMAN WESTLING, OF HUDSON, MASSACHUSETTS, ASSIGNOR TO APSLEY RUBBER COMPANY, OF HUDSON, MASSACHUSETTS, A CORPORATION OF MASSACHUSETTS.

SHOE.

1,349,744.

Specification of Letters Patent. Patented Aug. 17, 1920.

Application filed November 24, 1919. Serial No. 340,165.

To all whom it may concern:

Be it known that I, HERMAN WESTLING, a citizen of the United States, residing at Hudson, in the county of Middlesex and State of Massachusetts, have invented a certain new and useful Improvements in Shoes, of which the following is a specification, reference being had therein to the accompanying drawings.

10 The invention relates especially to rubber-soled shoes, and more particularly to rubber-soled canvas shoes.

One objection to rubber-soled canvas shoes as heretofore made has been the somewhat 15 clumsy appearance due to the manner in which the upper is connected with the sole and also to the formation of the heel. Usually as heretofore constructed the shoe is made without a welt and therefore lacks the

20 finished appearance which the leather shoe has, due to the welt. Sometimes a welt has been employed of special form and which runs entirely around both the sole and heel portion of the upper of the shoe, whereas in 25 the ordinary leather shoe the welt terminates at the heel. Moreover the heel portion has usually been formed integral with the rubber outer sole of the shoe and is produced by giving an increased thickness to

30 the heel portion of the sole during the manufacture of the sole, or sometimes the heel has been made separate and cemented or vulcanized onto the sole. The object of the present invention is to produce a rubber- 35 soled canvas shoe having a welt which terminates at the breast of the heel and having a separate heel attached to the shoe by

nails or other metallic fastenings, so that in 40 outside appearance the shoe will resemble the makeup of a welted leather shoe having a heel attached thereto by cement, nails or other metallic fastenings. Another object of the invention is to provide such a construction that the heel portion of the sole

45 may be attached to the upper and the insole by nails before the heel is attached, and then have the heel attached separately. In the ordinary method of construction of rubber-soled canvas shoes it is impossible 50 to firmly secure the heel portion of the outer sole to the upper inner sole by nails, because the nails have a tendency to draw through the rubber sole. One object of the invention is to provide a stay member on the

55 lower face of the heel portion of the sole to

serve as a stop to prevent the heads of the nails from coming in contact with the under face of the rubber sole, and thereby to prevent the heads of the nails from drawing up into the rubber.

60 The invention will be fully understood from the following description when taken in connection with the accompanying drawings, and the novel features thereof will be pointed out and clearly defined in the claims 65 at the close of this specification.

In the drawings, Figure 1 is a vertical sectional view of a shoe after it has been lasted, and having the heel stay member of the invention attached to the outer sole.

70 Fig. 2 is a detail plan view of the stay member.

Fig. 3 is a plan view of the shoe shown in Fig. 1.

Fig. 4 is a view partly in section showing 75 the shoe after the heel has been attached.

Referring now to the drawings, 1 represents the canvas upper, 2 the insole, 3 the welt, and 4 the outer sole. The welt 3 is secured to the upper and insole preferably 80 by stitches 5; the welt extends around the forepart and shank of the shoe and terminates as shown in Fig. 4, just back of the breast portion of the heel.

85 The upper, welt and inner sole having been united together in any suitable manner, the heel portion of the upper is lasted in by means of tacks 15 after the usual manner of lasting, the tacks being driven through the turned under portion of the 90 canvas upper and through the inner sole and counter. Then the outer sole 4 is laid upon the inner sole and cemented to the inner sole excepting as to the heel portion

thereof which at that time is left free. 95 Then there is applied to the heel portion of the outer sole a heel shaped piece 6 of canvas, or other suitable fabric, canvas being preferred, and preferably the canvas should be rather thick and stout. This 100 canvas heel piece has the contour of the heel portion of the outer sole, except preferably of slightly smaller dimension, so that there is a slight margin outside of the canvas heel

piece 6, as will be seen in Fig. 3. The reason 105 for making the canvas heel piece of slightly smaller size than the heel portion of the outer sole is so that the canvas will not be exposed at the edge of the finished shoe.

110 The canvas piece 6 is cemented to the outer

sole to retain it in position, and then a row of nails 7 are driven through the canvas heel piece 6 around near its margin, said nails passing through the outer sole and the inturned portion 8 of the upper and through the inner sole 2 and counter, and they are clenched on the inside of the inner sole, as shown in Fig. 4.

The heads 9 of the nails bear directly 10 against the canvas heel piece 6 which thus serves as a stay or washer and is of sufficient strength to prevent the head of a nail from drawing through, whereas if the canvas piece were not employed and the head 15 of the nail rested directly against the face of the outer sole, the head of the nail would wear on the rubber and either wear through or at least wear loose. The use of the canvas piece 6 is much preferred to the use of 20 a metallic piece, because the nails can be driven anywhere through the canvas piece without the necessity of having them register with any particular hole as would be required if any metallic plate were employed, and, furthermore, the canvas is more 25 flexible. Then the heel 10 may be applied and secured in any suitable manner, as for instance by the ordinary method of securing a rubber heel to a leather shoe either by 30 cement or by metallic fastenings driven through apertures in the rubber heel and then into the heel seat and clenched.

What I claim is:—

1. A rubber-soled canvas shoe having a 35 canvas upper, an inner sole, and a welt all united together, the welt extending around the forepart and the shank and terminating at points substantially opposite the breast of the heel and outer sole, the rubber sole secured to the inner sole throughout the forepart and shank, a layer of canvas attached to the outer face of the heel portion of the outer sole, and fastenings nails which pass through 40 said canvas layer and through the outer and inner soles, the nails having heads which bear against the outer face of said canvas layer.

2. A rubber-soled canvas shoe, having a 50 canvas upper, an inner sole, and a welt all united together the welt extending around the forepart and the shank and terminating at points substantially opposite the breast of the heel, the turned-under heel portion of the upper and of the inner sole being fastened 55 together by tacks passing through the

turned-under portion of the upper and counter and the inner sole, an outer sole of rubber adhesively secured to the inner sole throughout the forepart and shank, a layer of canvas shaped to the contour of the heel 60 and attached to the outer face of the heel portion of the outer sole, and fastening nails which pass through said canvas layer, the outer sole, the under-turned portion of the upper and the inner sole.

3. A rubber-soled canvas shoe, having a canvas upper, an innersole, and a welt all united together, the welt extending around the forepart and the shank and terminating at points substantially opposite the breast 70 of the heel, the turned-under heel portion of the upper and counter and the inner sole being fastened together by tacks passing through the turned-under portion of the upper and inner sole, an outer sole of rubber 75 secured to the inner sole throughout the forepart and shank, a layer of canvas shaped to the contour of the heel but somewhat smaller than the heel portion of the outer sole, so that the periphery of the outer sole, extends 80 outward slightly farther than the periphery of the canvas layer and attached to the outer face of the heel portion of the outer sole, and fastening nails which pass through said canvas layer, the outer sole, the under-turned 85 portion of the upper and the inner sole.

4. A rubber-soled canvas shoe, having a canvas upper, an inner sole, and a welt all united together, the welt extending around the forepart and the shank and terminating 90 at points substantially opposite the breast of the heel, the turned-under heel portion of the upper and counter and of the inner sole being united together, an outer sole of rubber adhesively secured to the inner sole 95 throughout the forepart and shank, a layer of canvas shaped to the contour of the heel and attached to the lower face of the heel portion of the outer sole, and fastening nails which pass through said canvas layer, 100 the outer sole, the under-turned portion of the upper and counter and the inner sole, and a rubber heel as a separate article attached to the outer sole, the said canvas heel piece lying between the said attached heel 105 and the outer sole.

In testimony whereof I affix my signature.

HERMAN WESTLING.
